DESIGN FOR A LAPEL EMBLEM BUTTON OR THE LIKE

Henry Rabkin, Washington, D. C., assignor to the
United States of America, as represented by
Chester C. Davis, Administrator of the War
Food Administration, and his successors in
office

Application June 24, 1943, Serial No. 110,511

Term of patent 3½ years

To all whom it may concern:

Be it known that I, Henry Rabkin, a citizen of
the United States of America, residing at 1315
Peabody St., N. W., Washington, D. C., have in-
vented a new, original, and ornamental Design
for a Lapel Emblem Button or the like, of which
the following is a specification, reference being
had to the accompanying drawing, forming part
thereof.

Figure 1 is a front view of a lapel emblem but-
ton or the like, showing the new design;

Figure 2 is a rear view of the same; and

Figure 3 is an edge view thereof.

The essential features are shown in Figure 1.

While the design shown is embodied in the
form of a button or badge, it is understood that
the same may be embodied as an insignia in other
similar articles.

I claim:

The ornamental design for a lapel emblem but-
ton or the like, substantially as shown and de-
scribed.

HENRY RABKIN.
